ATTORNEY.

UNITED STATES PATENT OFFICE

ANTONIO CIRAOLO, OF OAKLAND, CALIFORNIA

IGNITION DEVICE

Application filed July 23, 1927. Serial No. 208,030.

My invention relates to a new type of match and to means for igniting the same. This application is a continuation in part of my copending application Serial No. 142,269, filed October 18, 1926, directed to orchard heaters.

It is the object of my invention to provide a generally improved ignition device. It is an object of my invention to provide a match and igniter therefor especially adapted for easy and automatic ignition.

Other and ancillary objects of my invention will be suggested in the following description and in the use of the device of my invention. Certain of the objects, or certain portions or combinations of the objects of my invention may be attained with the use of less than all its advantageous features, or with modifications within its purview. It is petitioned therefore, that my invention be limited only by the claims constituting its final determination.

Referring to the drawings:

Fig. 1 is a magnified perspective view of the ignition device of my invention with a segment broken away to disclose the radial section thereof. Fig. 2 is a transverse section of the upper portion of the ignition device; the section being taken through the ignition tip of the match. Fig. 3 is a diagrammatic sketch of the ignition device of my invention incorporated in an oil burner and adapted to automatically ignite the oil burner. The view is a vertical section through the burner disclosing the ignition device in side elevation. Fig. 4 is an elevation of the threadlike member of the ignition device. Fig. 5 is a radial section, similar to Fig. 1, of a modified form of the placement of the threadlike member of the ignition device. Fig. 6 is a front elevation of a modified ignition device in which the threadlike member constitutes the match instead of the igniter therefor.

The match of my invention is formed of an

annular cylindrical wick 1, preferably of pervious cardboard, adapted to rest with its lower end immersed in oil or other fluid combustible 2 (Fig. 3) which it is desired to ignite; the cardboard thus becoming saturated with combustible.

As alternative to this arrangement, I may impregnate the cardboard with paraffine or other combustible, and employ it for ignition of substances other than the fluid combustible 2, or the match body may be made of wood or other inherently combustible material. I prefer the annular cylindrical shape because of its greater capillary action, greater strength, and greater surface area; the large surface area being particularly advantageous as stimulating combustion and because it provides for a greater surface of ignition tip on the match. Other advantages of this shape will suggest themselves, but I desire not to be limited thereto, as certain valuable features of my invention are not dependent upon employment of this particular shape of member 1.

The upper part of member 1 is tipped with a coating 3 (Figs. 1 and 2), of readily ignitable material which may be set off by friction, or chemical action or both. For instance where the match is to be supported adjacent to a burner to be lit, a metal clip 4 is provided and secured to the lower part of member 1 by rivets or other convenient means; the clip being adapted to secure the match to a surface such as the rim of a cup 5 containing oil to be fired.

An igniter 6 is provided to initiate ignition of the match. This igniter has two most important characteristics; it is of threadlike extent, and it is flexible. The igniter is preferably formed on ordinary string such as is used in wrapping packages. The string is coated for an appreciable portion of its length with an ignition-producing material complementary to that of the tip 3, and is

wound part way around the tipped portion of the cylinder 1.

The igniter is brought into intimate contact with the match by a resilient metal clip 8 straddling the top of the wall of the member 1 and urging the thread 6 against the tip 3. When the thread is pulled the coating 7 is scratched across the tip 3, causing it to ignite.

10 The thread is held against the match, and, together with the match, is protected from moisture, by a sufficiently heavy paraffine coating 9 over the assembled match and igniter. It will frequently be advantageous to 15 apply the paraffine coating with the coated portion 7 of the thread in intimate contact with the ignitable tip 3, but as illustrated in Fig. 2, it is safer to allow a thin wax coating to separate the ignition-producing material 20 7 from the tip 3. This may be accomplished by thinly coating about one quarter of the circumference of the match tip with paraffine 9', then laying the thread with its igniting portion 7 over this paraffine, and with 25 the friction-producing clip 8 holding an uncoated portion of the thread against a non-paraffined portion of the tip surface. After this, the entire assembly may be dipped to provide its final paraffine coat 9.

30 The ignition device of my invention is especially susceptible to automatic actuation. It is merely necessary to connect the flexible string 6 to a trigger placed in almost any desired position; without thought as to relative 35 placement of a separate match and striker therefor. An illustrative trigger arrangement is diagrammed in Fig. 3, wherein a spring 10 is connected at one end to the string 6 and at the other end to any suitable support 11. The spring is held extended by a 40 knife edge 12 inserted between its coils and attached integrally to the movable edge of a bi-metal thermostat 13, and is adapted to be withdrawn below the surface of a second support 14 when the thermostat is cooled 45 down below a predetermined temperature, this type of control being particularly designed for use in lighting orchard heaters.

The clip 8 is not an essential element. The 50 match will usually ignite without it, especially if the thread 6 is wrapped around the tip 3. The clip, however, insures unfailing action of the ignition device. Although it is preferable to wind the thread 55 circumferentially around a segment of the tip, it may be placed longitudinally against the tip in other positions. One such other position is shown in Fig. 5, wherein the match is formed on a flat-sectioned wooden 60 stick 1', is provided with a tip 3', a friction-producing clip 8 and paraffine coating 9; the igniter thread 6 being positioned parallel to the longitudinal axis of the match 1'. The 65 essential prescription of this feature of my invention is that the coated part of the

70 threadlike member be placed longitudinally against the tip surface. The thread 6 may then be moved longitudinally of itself in striking the match. The thread 6, being flexible, may be subjected to pure tensile pull in 75 striking the match. There is no scraping scratching motion required, and the thread may thus be made as limp as desired. It need have structural strength only in tension.

When the thread is pulled for striking the match, the paraffine coat 9 is arranged to crack, and more or less flake off, at the wick portion initially engaged by the coated string end whereby the wick is exposed for 80 burning at its ignition point. The paraffine, being combustible and fusible, is burned or melted away from the remaining coated wick portion until the entire wick is ignited. It is noted that the temperatures prevailing 85 at the device when the latter is applied in association with an orchard heater used for protection against frost, would be such that a coating of ordinary commercial paraffine would be in a brittle state for fracturing as described. Having in mind the fact that the 90 binding and moistureproofing coating 9 must be of material which is combustible and fracturable at the temperature at which the igniter is used, it is to be understood that other materials having said qualities might be 95 used in lieu of paraffine for effecting the desired result.

99 The tip 3 and coating 7 may be of any desired complementary ignition materials. For the tip 3 I prefer the compound commonly used in the tips of so-called safety matches, consisting of chlorate and bichromate of potash, red lead, and antimony sulfide; and for the coating 7 I would then use 100 a combined friction and chemical ignitant 105 comprising a mixture of amorphous phosphorous and antimony sulfide.

110 While it is advantageous in the described embodiment of my invention, to place the major combustible in the tip 3, and the ignitant in the coating 7, this relation may be inverted so that the thread 6 becomes the match, and the tip 3 becomes the striker. Such a modification is illustrated in Fig. 6 115 wherein a cylindrical bar 15 of sandstone, 120 cast iron, or other rough material, forms the striker; the match 16 being a flexible thread having a friction-ignitable coating 17 near one end. The coated end of the match is hung over the striker 15 and is preferably wound once around the striker, so that the coating 17 will be scratched across the 125 striker when the free end of the match is pulled. A plurality of such matches might be carried in spaced relation on a single striker.

130 Attention is especially directed to the ease with which the ignition devices of my invention may be operated. In each case the device is operated by simply indiscriminately

pulling a string; it being unnecessary to seek a suitable scratching surface, or to adjust the pressure exerted thereon. The match never breaks nor fails to light. These features dispose the ignition devices of my invention particularly to uses such as that described in my copending application Serial No. 142,269, filed October 18, 1926, where dependability and ease of operation are prime considerations.

I claim:

1. Igniting means for a match, comprising an igniter member removably secured to and against the ignition head of the match and arranged to effect the ignition of said head by and upon its removal, and fracturable means operative to releasably and directly secure said match and member together whereby one supports the other prior to the removal of said member.

2. Igniting means for a match, comprising a member having an igniting head removably carried on the ignition head of the match, and fracturable means jointly enshrouding said heads for securing them together in sealed-in relation.

3. Igniting means for a match having an ignition head, comprising a member having an igniting head, and a shroud of combustible material securing said heads together and fracturable to permit a relative contacting movement of said heads for effecting the ignition of said match head and to expose the match head for burning.

4. Igniting means for a match having an ignition head, comprising a member having an igniting head, and a moisture-proof shroud securing said heads together and fracturable to permit a relative separation of said heads, and means cooperative between the match and member for guiding them to effect a frictional engagement of the heads during said separation thereof for igniting the match head.

5. Igniting means for a friction match having an ignition head, comprising an igniter member formed of a flexible thread provided with an igniting head unitarily secured to and against the match head and arranged when the match and member are pulled apart to be longitudinally drawn against the surface of said ignition head for igniting the same.

6. In combination with a match, an igniter therefor, and a fracturable bonding material directly securing the respective heads of said match and igniter and cooperative in unitary association and for frictional engagement thereof when separated.

7. In combination with a tubular body of combustible material provided with an integral ignition head to ignite said material, a member providing an igniting head directly and removably mounted on and against said ignition head whereby a re-

moval of the member is arranged to effect a frictional engagement of said heads for igniting said ignition head.

8. In combination with a match having an ignition head, a member having an igniting head for frictional engagement with said ignition head, a moisture-proof shroud jointly enclosing said heads and fracturable upon a relative contacting movement of said heads to expose said ignition head and match for burning.

In testimony whereof I affix my signature.

ANTONIO CIRAOLO.
